Primary Examiner — L. A. Grabenstetter(74) *Attorney, Agent, or Firm* — Syncoda LLC; Feng Ma(57) **CLAIM**

The ornamental design for a host for television, as shown and described.

DESCRIPTION

1.-2. Host for television

1.1 is a front view thereof of a host for television showing our new design;

1.2 is a rear view thereof;

1.3 is a left view thereof;

1.4 is a right view thereof;

1.5 is a top view thereof;

1.6 is a bottom view thereof;

1.7 is a bottom perspective view thereof; and

1.8 is a top perspective view thereof.

The broken lines, and regions surrounded on all sides by broken lines, depict portions of article that form no part of the claimed design.

1 Claim, 8 Drawing Sheets(56)
